DESIGN FOR A GARDENIA MOUNT

Edward J. Brumder, Milwaukee, Wis., assignor to The North American Press, Milwaukee, Wis.,
a corporation of Wisconsin

Application November 4, 1943, Serial No. 111,597

Term of patent 7 years

To all whom it may concern:

Be it known that I, Edward J. Brumder, a citizen of the United States, residing at Milwaukee, in the county of Milwaukee and State of Wisconsin, have invented a new, original, and ornamental Design for Gardenia Mount, of which the following is a specification, reference being had to the accompanying drawing, forming part thereof, and in which:

Fig. 1 is a plan view of a gardenia mount, showing my new design; and

Fig. 2 is a view thereof in cross section taken on line 2—2 of Fig. 1.

I claim:

The ornamental design for a gardenia mount, as shown.

EDWARD J. BRUMDER.
